UNITED STATES PATENT OFFICE.

JOHN BRIGGS, OF ROXBURY, MASSACHUSETTS.

IMPROVEMENT IN DRAFT-REGULATORS FOR STOVES AND FURNACES.

Specification forming part of Letters Patent No. 41,598, dated February 16, 1864.

To all whom it may concern:

Be it known that I, JOHN BRIGGS, a resident of Roxbury, in the county of Norfolk and State of Massachusetts, have made a new and useful Invention for Regulating the Draft of a Stove or Furnace; and I do hereby declare the same to be fully described in the following specification, and represented in the accompanying drawings, of which—

Figure 1 denotes a top view, Fig. 2 a side elevation, and Fig. 3 a vertical section, of a hot-air furnace and my invention applied thereto.

In the said drawings, A denotes the outer case of the air-heating space or chamber B, which surrounds a stove or heating-furnace, C, provided not only with an air-induction pipe, D, but a smoke or eduction pipe, E:

On the top of the case A there is placed an air-tight drum, F, made of tin plate or other suitable material, it being furnished with a conical or other proper-shaped standard, G, to serve as the fulcrum of one or two levers, H I, arranged horizontally on it, as shown in the drawings. This standard I usually make hollow and air-tight, and so rest or support it on the drum that its base may expand, as the head of the drum may, when the air or fluid within the drum may be heated. In this case the standard becomes an auxiliary drum or expansion-vessel.

Each lever at one end is supported by a rod, K or K', which not only projects upward from the top of the case A, or is hooked into a staple, a, extending from such top, but goes through the lever, and is provided with a screw, b, and a nut, c, at its upper end or part, as shown in the drawings.

From the other extremity of the lever a rod, L, depends, and is to be either directly or indirectly connected with a valve-stem, d. In the figures the rod L is represented as having a helical spring, e, interposed between it and the valve-stem. The valve M of the stem is a hollow cylindrical vessel, open at bottom and closed at top, and provided with one or more elongated openings, f f, made through its sides, such valve being caused to encompass and be capable of moving vertically on a cylindrical pipe, g, projected upward from the induction-pipe D, and being closed at its upper end and furnished with a series of elongated openings, h h, made through its sides.

The pipe g, at its lower end, opens into the induction-pipe. A stop, i, is applied to a wire, k, projecting from the tube g, as to be capable of being slid up and down on such wire, is to be inserted in one of a series of holes, k' k' k', made in the side of the tube g, the object of the stop being to determine the height to which the valve may be raised on the tube g. The drawings also represent a valve, M', as applied to a tube, g', extending up from and opening out of the eduction-pipe, the said valve M' being made with perforations or air-inlets m m, and being duly suspended from the lever I.

The suspension-rod of each valve goes directly through its lever, but does not screw into it. Such rod, however, is provided at its upper part with a screw, n, and nut o, arranged on it and with respect to its lever, as shown in the drawings. The said screw and nut serve as a means of adjusting the valve relatively to the lever.

Although I have represented in the drawings my invention as applicable to the induction and eduction pipes of the heating-stove of the hot-air furnace, I wish it understood that it may be applied to only one of these pipes, or it may be applied to both of them, as may be desirable, in which latter case one expansion-drum will answer for both pipes. It is sometimes the case that when the invention is applied to both of the pipes the regulation of the combustion of the fuel of the furnace, and of course that of the heat produced, will be better than if it were applied to one of these pipes only.

In the operation of the invention the air or fluid which may be within the drum F will be expanded by the heat which may be conducted into it from the case of the air-chamber or furnace, the drum being so connected with or applied to such case or furnace as to enable the heat to be readily conducted into it. The expansion of the air or fluid acting on the upper head of the drum will raise the same, or cause it to be more or less convex, and so as to elevate the fulcrum of the lever in a manner to produce a movement of the valve—that is to say, the valve of the induction-pipe will be moved so as to reduce the openings for the entrance of air into such pipe; but the valve of the eduction-pipe will be raised in a manner to increase the area of its air-openings, in

order to allow more air to pass into the discharge-flue.

The expansion-drum, as shown in the drawings, has two heads, *r* *s*, the lower of which is not supported directly on the top of the case *A*, but on a short standard or seat-disk, *t*, resting thereon, and having a diameter less than that of the drum. This enables the lower head of the drum to contract and curve inward and aid in producing a movement of the lever, such as would not be produced were the drum-head to rest at its periphery directly on the top of the case *A*.

The spring placed between the stem of the eduction-pipe valve and rod of the lever thereof will operate to prevent breakage of the rod by the strain of the lever while the valve may be elevated or brought up against its stop.

Air or any expansive fluid or liquid suitable for the purpose may be used in the drum, it being understood that the said drum is to be filled with the same and to be made with either

or both its heads, and particularly its upper head, of a flexible material, such as will allow of the ready and proper expansion of the head under the expansion of the air or fluid induced by its absorption of heat.

I am aware that rods and various other contrivances have been used to regulate by their expansion by heat a valve or damper of a flue or pipe of a stove or furnace, and therefore I make no claim to such, my invention being an improvement over such.

I claim—

The improved draft-regulator, consisting of the expansion-drum *F*, its lever *H*, the valve *M*, and the adjustable stop *i*, and spring *e*, the whole being applied to a furnace or heating apparatus, and constructed in manner and so as to operate substantially as described.

JOHN BRIGGS.
